[57] CLAIM

The ornamental design for a brake light display cover, as shown and described.

DESCRIPTION

FIG. 1 is a front elevational view of the brake light display cover of the present invention;

FIG. 2 is a rear elevational view of the brake light display cover of FIG. 1;

FIG. 3 is a left side elevational view of the brake light display cover of FIG. 1, the right side elevational view being a mirror image thereof; and,

FIG. 4 is a top plan view of the brake light display cover of FIG. 1, the bottom plan view being a mirror image thereof. The broken lines showing of a brake light in FIGS. 2 through 4 are for illustrative purposes only and form no part of the claimed design.
